UNITED STATES PATENT OFFICE.

EARL C. STAFFORD, OF WILKINSBURG, PENNSYLVANIA, ASSIGNOR TO THE RAILWAY AUTOMATIC SAFETY APPLIANCE COMPANY, OF PHILADELPHIA, PENNSYLVANIA, A CORPORATION OF DELAWARE.

AUTOMATIC TRAIN-STOP.

1,249,685.

Specification of Letters Patent. Patented Dec. 11, 1917.

Application filed May 1, 1915, Serial No. 25,111. Renewed May 5, 1917. Serial No. 166,768.

To all whom it may concern:

Be it known that I, EARL C. STAFFORD, a resident of Wilkinsburg, in the county of Allegheny and State of Pennsylvania, have invented certain new and useful Improvements in Automatic Train-Stops, whereof the following is a specification, reference being had to the accompanying drawings.

The invention relates to an improved mechanism for automatically applying the brakes for railway trains, and more particularly to a mechanism for stopping trains, which may be controlled from outside sources, such as signal stations or the like.

It is one object of my invention to provide a valve to control the air brakes, capable of use in connection with a third rail, which shall be subject to both electrical and mechanical control, either one of which will serve to keep the valve from operating.

A further object of my invention is to provide a valve so constructed that the third rail may be utilized as a means common to both the mechanical and electrical control.

It is characteristic of my invention that the valve is kept normally closed so as to prevent the application of the brakes, by a spring held under compression by an electrically controlled latch, as well as a mechanically controlled locking device, both of which must be released before the valve can open. It is also characteristic that the means for releasing the mechanical control may also be utilized as a means of electrical contact for regulating the electrical control.

Such a device may be used in connection with any automatic train stop system, as for example in such a system as is described in an application executed and filed by me on

April 21st, 1915, Serial Number 22,775.

Referring to the accompanying drawings, Figure I, is a diagrammatic front elevation of my automatic valve system, showing the two means of control.

Fig. II, is an enlarged view in side elevation of the valve itself.

Fig. III, is a longitudinal sectional view of the same.

Fig. IV, is a transverse sectional view on the line IV, IV, of Fig. III.

The valve itself consists of a valve chamber 1, which is connected with a pipe 2, which is in turn connected with the drain pipe 3. Located within the chamber 1, is

the valve 5, which engages a valve seat 6. 55 A rod 7, supports the valve, and extends through a sleeve 8, which is adjustably mounted in the cap closing the lower end of the valve chamber. The rod 7, slides freely in this sleeve 8, and is forced upwardly by a spring 9, which engages at one end, the under face of the valve, and at the other end, the sleeve 8, which may be adjusted for the purpose of increasing or decreasing the tension of the spring 9. 60

An outlet 10, for the valve chamber, is closed by a plug 11, provided with an opening 12. This plug may be readily removed and a plug having a different sized opening substituted, so as to vary the control of the 70 release of the air through the valve chamber, and consequently the speed with which the brakes are applied. The valve rod 7, extends through a guiding lug 15, carried by a bracket 16, and also through a sleeve 17, 75 which, in turn, is mounted in a lug 18, carried by the bracket 16. The rod slides freely in this sleeve 17. A spring 19, rests on the sleeve 17, and bears against a collar 20, which is attached to the valve rod. The 80 valve rod 7, is further guided by a lug 21, which is carried by a bracket 22, and is in line with the adjustable screw 23, which will limit the downward movement of the valve rod, under the action of the air against the 85 valve when the tension of the spring 19, is released. The sleeve 17, is vertically shiftable in the guiding lug 18, and may be held in raised position by a swinging latch 25, which is pivoted at 24, to a bracket 26. 90

When the sleeve 17, is raised and the spring 19, operates under compression, the valve 5, is held seated. When, however, the sleeve 17, is released, and the spring 19, becomes substantially ineffective, the air pressure is 95 then sufficient to overcome the tension of the spring 9, and will open the valve 5, and thus release the air, and permit the setting of the brakes. Adjacent its lower end, the valve rod 7, is provided with a slot which engages the outer end of a rocker arm 30. This rocker arm is pivoted at 31, to the bracket 22, and has a downward projecting arm 32.

The third rail shoe 40, is pivoted at 41, to a bracket 42, which may be adjustably attached to a supporting block 43, which is preferably insulated or of insulating material, so as to prevent grounding of the shoe 105

through its supporting connection. A spring 44, coöperates with the supporting arm for the shoe 40, and normally holds the same raised. At the lower end of the arm 32, is a plate 33, which is insulated from, but rigidly attached to the arm 32, by suitable bolts 34.

When the shoe 40, is in the position shown in Fig. I, of the drawings, the rocker arm 30, is released, and the valve rod 7, is free to move up and down, except for the controlling latch 25. If this latch 25, is ineffective, then the air will open the valve and permit the application of the brakes, while on the other hand, if the latch is effective, then the release of the rocker arm 30, merely shifts the control of the automatic train stop to the latch 25. If the shoe 40, is raised through the action of the spring 44, an upwardly projecting arm 45, carried by the shoe 40, will engage the plate 33, and will prevent the arm 30, from swinging, and the shoe 40, thus becomes effective to hold the valve 5, closed, to prevent the application of the brakes. In other words, when the shoe 40, is out of contact with the third rail 48, it is effective at all times to prevent the application of the brakes by the action of the valve. While when the shoe is in contact with the third rail, it is drawn downward, so as to mechanically release all control of the valve.

Formed integrally with latch 25, is an arm 27, which extends outwardly from the bracket and carries an armature 28, held in operative relation to the electro-magnet 29. When the magnet is energized, the armature is held against it, and the latch occupies the position shown in Fig. I, thereby locking the valve and preventing the application of the brakes. When, however, the magnet is deenergized, the arm 27, is no longer held against it, but is free to turn on its pivot 24, thereby releasing the latch 25, and the spring 19. In this way the electrical control is provided. But since, as has been pointed out, the shoe 40, serves to lock the valve when in the raised position, the electrical control becomes effective only when the shoe is lowered and the mechanical control released.

Located in the pipe 2, is a valve 50, which is controlled by an arm 51, which may be sealed in any well known way. If the train stop becomes ineffective for any reason, the seal of the valve may be broken, and the train stop entirely cut out, which will enable the engineer to proceed, but which will also indicate to an engine inspector, that for some reason the train stop has become deranged and requires attention as to repairs.

In operation, the shoe 40, is normally held in the raised position under the action of the spring 44, so that the valve is kept closed. 65 In this position it is immaterial whether

the latch 25, is closed or not. When, however, the shoe 40, comes in contact with a third rail, it is depressed and takes the lower position shown in Fig. I. The arm 32, is then free to swing and the valve 5, will open, unless it is held closed by latch 25, which occurs only when the electro-magnet 28, is energized. But since the shoe 40, is depressed only when in contact with the third rail, it is possible, by properly connecting the energizing coil of magnet 29, with the shoe 40, to energize the magnet whenever the third rail is energized. By connecting the third rail so that it is only energized when the signals are set for safety, it is possible to automatically stop all trains which attempt to pass a signal station not set for safety.

Having thus described my invention, I claim:

1. In an automatic train stop the combination of a valve chamber, a valve reciprocating therein, mechanical means normally tending to keep said valve seated, a spring adapted when placed under tension to keep said valve seated, and electrical means adapted to act independently of said mechanical means for controlling the tension of the spring.

2. In an automatic train stop, the combination of a valve chamber, a valve reciprocating therein, a valve rod connected with said valve extending beyond said valve chamber, a slot near the end of said valve rod, a rocker arm engaging said slot, and adapted in one position to hold said valve seated, and mechanical means for holding said rocker arm in this position.

3. An automatic train stop, including a valve chamber, a valve therein, a spring for normally holding said valve seated, a second spring coöperating with said first named spring, adapted when placed under tension to prevent the opening of the valve by the air pressure, and devices for controlling the compression of said second named spring.

4. An automatic train stop, including a valve chamber, a valve therein, a spring for normally holding said valve seated, a second spring coöperating with said first named spring, adapted when placed under tension to prevent the opening of the valve by the air pressure, and devices for controlling the compression of said second named spring said valve chamber having an opening leading therefrom and an apertured plug for closing said opening.

5. An automatic train stop, including a valve chamber, a valve therein, a valve rod, connected to said valve, a collar attached to said valve rod, a spring in the valve chamber, normally tending to hold the valve seated, said valve chamber having an outlet opening, an apertured plug for closing said outlet opening, a spring surrounding the

valve rod, outside of said chamber, and engaging the collar, and an adjustable sleeve forming an abutment for the other end of said spring, and means for holding said sleeve for placing the last named spring under compression.

6. An automatic train stop, including a valve chamber, a valve therein, a valve rod, connected to said valve, a collar attached to 10 said valve rod, a spring in the valve chamber, normally tending to hold the valve seated, said valve chamber having an outlet opening, an apertured plug for closing said outlet opening, a spring surrounding the 15 valve rod, outside of said chamber, and engaging the collar, an adjustable sleeve forming an abutment for the other end of said spring, means for holding said sleeve for placing the last named spring under 20 compression, a rocker arm pivoted to the lower end of said valve rod, and devices coöperating with said rocker arm for holding said valve seated.

7. An automatic train stop, including a 25 valve chamber, a valve therein, a valve rod

connected to said valve, a collar attached to said valve rod, a spring in the valve chamber, normally tending to hold the valve seated, said valve chamber having an outlet opening, an apertured plug for closing said 30 outlet opening, a spring surrounding the valve rod, outside of said chamber, and engaging the collar, an adjustable sleeve forming an abutment for the other end of said spring, means for holding said sleeve 35 for placing the last named spring under compression, a rocker arm pivoted to the lower end of said valve rod, devices coöperating with said rocker arm for holding said valve seated, and an adjustable screw for 40 limiting the movement of the valve rod when said valve is unseated.

In testimony whereof, I have hereunto signed my name, at Philadelphia, Pennsylvania, this thirtieth day of April, 1915.

EARL C. STAFFORD.
